OP D 13,467

No. 13,467

DEC 5, 1882

UNITED STATES PATENT OFFICE

JAMES H. FLYNN AND JACOB A. SNELL, OF SCHENECTADY, NEW YORK.

DESIGN FOR A WHISK-BROOM CASE.

SPECIFICATION forming part of Design No. 13,467, dated December 5, 1882.

Application filed October 24, 1882. Term of patent 7 years.

To all whom it may concern:

Be it known that we, JAMES H. FLYNN and JACOB ARTHUR SNELL, citizens of the United States, residing at Schenectady, in the county 5 of Schenectady and State of New York, have invented and produced a new and original Design for Whisk-Broom Cases, of which the following is a specification, reference being had to the accompanying illustration, forming part 10 thereof.

A is the whisk-broom case, having the general form of the brush, open at the top and bottom. Bands *a a* are placed around the case at the top and bottom parallel to the edge; 15 but these bands may be omitted. Between the bands, on the body of the case, may be placed one or more ornaments, *b*.

B is the back of the whisk-broom case, made in the general form of an anchor.

20 The case A is attached to the part corresponding to the shank of the anchor, and by preference in such relation thereto that the said shank lies across the back of the case obliquely, so that the head of the anchor is on 25 one side of the case and the flukes on the opposite side, as shown.

The points of the flukes may be provided with ornaments *b' b'*, and the lower fluke, *c*, may be so placed relatively to the case that 30 when the whisk-broom D is placed in the case the shoulders of the whisk-broom rest between

the case and the fluke *c* in the manner shown. The ends of the cross-head of the anchor may also be provided with ornaments *d*.

We claim—

1. The design for a whisk-broom case herein shown, which consists in the case A, having bands *a a*, and anchor-shaped back B.
2. The design for a whisk-broom case, which consists in the case A, having ornament *b*, and anchor-shaped back B.
3. The design for a whisk-broom case, which consists in the case A, having bands *a a* and ornaments *b*, and anchor-shaped back B.
4. The design for a whisk-broom case, which consists in the tapered case A and anchor-shaped back B, having its fluke *c* so placed relatively to the case that the shoulders of the whisk-broom lie between the fluke and case.
5. The design for a whisk-broom case, which consists in the case A, placed upon a back, B, having the general form of an anchor, and arranged obliquely to the case, as shown.
6. The design for a whisk-broom case herein described and shown, the same consisting of an anchor-shaped back, B, and case A.

JAMES H. FLYNN.
JACOB ARTHUR SNELL.
